UNITED STATES PATENT OFFICE.

ARTHUR R. McARTHUR AND FRED F. POLK, OF GARY, INDIANA, ASSIGNEES TO AMERICAN SHEET AND TIN PLATE COMPANY, OF PITTSBURGH, PENNSYLVANIA, A CORPORATION OF NEW JERSEY.

HOOK.

Application filed April 1, 1926. Serial No. 39,003.

This invention relates to carrying hooks and more particularly to carrying hooks particularly adapted for carrying tin plate and the like, and has for its object the provision of a hook of this class having a novel form of operating mechanism adapted to operate the hook members.

Another object of this invention is to provide a hook of the class described having the novel construction, design and combination of parts hereinafter described and illustrated in the accompanying drawings.

In the drawings:

Figure 1 is a side elevation of a hook constructed in accordance with this invention.

Figure 2 is a top plan thereof.

Figure 3 is an end elevation thereof.

Figure 4 is a fragmentary side elevation 20 of the upper portion of a hook embodying this invention, with part of the carrying frame broken away for the sake of clearness.

Figure 5 is a fragmentary view showing 25 the operating cams in engagement with the lever arms of the hooks.

Referring more particularly to the drawings, the letter A designates the carrying frame of the hook mechanism as a whole, 30 which frame is composed of a pair of side bars 2 and end axle members 3 secured thereto.

Crank-shaped hook members 4 are pivotally mounted at their crank points, as at 35 4^a, on the axles 3 at each corner of the frame A. The hook members 4 each have one arm 5 extending inwardly parallel with the side bars 2 and forming an operating lever arm, while the other arm 6 of each of the hook members extends downwardly forming article engaging arms which terminate in hooked ends 7.

The lever arms 5 of the members 4, suspended from the opposite corners of the same side of the frame A, have their inner ends overlapped and one of the arms 5 is provided with a slot 8 to receive a pivot pin 9 carried by the other arm 5 so as to form a pivotal and sliding connection between the lever arms 5 of the pairs of members 4 on each side of the frame A.

The side rods 2 are each provided with a bearing lug 10^a intermediate their ends in which a shaft 10 is journaled. The shaft 10 has a pair of cams 11 secured there-

on and positioned to engage and depress the connected lever arms 5 of the members 4. A pair of cam-stop members 12 are secured on the shaft 10 and provided with projections 13 adapted to engage stop-blocks 14 on the side bars 2 to prevent the rotation of the cams 11 beyond their highest point.

The shaft 10 is provided with hand-wheels 15 at each end to provide for manual rotation thereof.

A suspension member or carriage B, composed of a crane hook plate 16 and substantially U-shaped carrier arms 17, is connected to the lever arms 5 of the hook members 4 by links 18 which are pivotally connected to the ends of the carrier arms 17 and to points intermediate the ends of the lever arms 5.

In operation the hand-wheels 15 will be 75 rotated to rotate the shaft 10 and cams 11 so as to force the cams 11 to depress the lever arms 5 and thereby rock the hook members 4 about their pivotal connections 4^a on the axles 3, and swing the article engaging arms 6 outwardly sufficiently to clear the plates or sheets to be lifted. The hook will then be lowered over the sheets or plates to be lifted, and the shaft 10 will be reversely rotated to move the cams 11 85 in the reverse direction and permit the arms 6 to swing inwardly toward the sheets so that the hook members 7 will engage under the sheets.

The stop members 12 and 13 will cooperate to prevent the moving of the cams 11 beyond their highest point and thereby prevent the arms 6 dropping against the material being lifted.

While we have shown and described one 95 specific embodiment of our invention, it will be understood that we do not wish to be limited thereto since various modifications may be made without departing from the scope of our invention as defined in the 100 appended claims.

We claim:

1. A carrying hook mechanism, comprising a substantially rectangular frame, a shaft extending transversely of and journaled in said frame intermediate the ends thereof, crank-shaped hook member pivotally suspended from each corner of said frame, said hook members having one arm extending inwardly parallel with the side members 105 110

of said frame to form operating lever arms and their other or article engaging arm extending downwardly and terminating in a hook portion, said hook members on the 5 respective sides of said frame having their lever arms connected together by a combined sliding and pivotal connection, and means on said shaft adapted to depress said lever arms when said shaft is rotated to swing said 10 article engaging arms outwardly to clear the articles to be lifted.

2. A carrying hook mechanism, comprising a substantially rectangular frame, a shaft extending transversely of and journaled 15 in said frame intermediate the ends thereof, crank-shaped hook members pivotally suspended from each corner of said frame, said hook members having one arm extending inwardly parallel with the side members 20 of said frame to form operating lever arms and their other or article engaging arm extending downwardly and terminating in a hook portion, said hook members on the respective sides of said frame having their 25 lever arms connected together by a combined sliding and pivotal connection, a suspension member adapted to be engaged by a crane hook, said member having a link connection with each of said lever arms intermediate 30 their ends, and means on said shaft adapted to depress said lever arms to swing said article engaging arms outwardly to clear the articles to be lifted.

3. A carrying hook mechanism, comprising 35 a substantially rectangular frame, a shaft extending transversely of and journaled in said frame intermediate the ends thereof, crank-shaped hook members pivotally suspended from each corner of said frame, 40 said hook members having one arm extending inwardly parallel with the side members of said frame to form operating lever arms and their other or article engaging arm extending downwardly and terminating in a hook 45 portion, said hook members on the respective sides of said frame having their lever arms connected together by a combined sliding and pivotal connection, a suspension member adapted to be engaged by a crane hook, 50 said member having a link connection with each of said lever arms intermediate their

ends, and cams on said shaft adapted to engage and depress said lever arms to swing said article engaging arms outwardly to clear the article to be lifted.

4. A carrying hook mechanism, comprising a substantially rectangular frame, a shaft extending transversely of and journaled in said frame intermediate the ends thereof, crank-shaped hook members pivotally suspended from each corner of said frame, 55 said hook members having one arm extending inwardly parallel with the side members of said frame to form operating lever arms and their other or article engaging arm extending downwardly and terminating in a hook portion, said hook members on the respective sides of said frame having their lever arms connected together by a combined sliding and pivotal connection, a suspension 60 member adapted to be engaged by a crane hook, said member having a link connection with each of said lever arms intermediate their ends, cams on said shaft adapted to engage and depress said lever arms to swing 65 said article engaging arms outwardly to clear the article to be lifted, and stops on said frame adapted to limit the movement of 70 said shaft and cams.

5. A carrying hook mechanism, comprising a substantially rectangular frame, a shaft extending transversely of and journaled in said frame intermediate the ends thereof, crank-shaped hook members pivotally suspended from each corner of said frame, 75 said hook members having one arm extending inwardly parallel with the side members of said frame to form operating lever arms and their other or article engaging arm extending downwardly and terminating in a hoop portion, a suspension member 80 adapted to be engaged by a crane hook, said member having a link connection with each of said lever arms intermediate their ends, and means on said shaft adapted to depress 85 said lever arms to swing said article engaging arms outwardly to clear the articles 90 to be lifted.

In testimony whereof, we have hereunto set our hands.

ARTHUR R. McARTHUR.
FRED F. POLK.
